UNITED STATES PATENT OFFICE.

ALFRED F. BORSCHEL, OF BUFFALO, NEW YORK.

VALVE SILENCER.

Application filed March 22, 1924. Serial No. 701,156.

To all whom it may concern:

Be it known that I, ALFRED F. BORSCHEL, a citizen of the United States, and a resident of Buffalo, in the county of Erie and State of New York, have made certain new and useful Improvements in Valve Silencers, of which the following is a specification.

My present invention relates generally to valves of internal combustion motors, and more particularly to the push rods and tappets or cross arms whereby either enclosed or overhead valves are actuated from the usual cam shaft, my object being the provision of means adaptable to both tappets and cross arms for the purpose of silencing the valves and preventing the usual noises brought about by engagement of these normally spaced apart valve actuating parts.

In the accompanying drawing which illustrates my present invention and forms a part of this specification,

Figure 1 is a vertical sectional view showing the practical application of my invention in connection with an enclosed valve,

Figure 2 is an enlarged detail side view partly in elevation and partly in section of my improved silencer applied to the tappet,

Figure 3 is a top plan view of Figure 2, Figure 4 is a side view of an overhead valve tappet illustrating the application of a slightly modified form of my invention applied thereto,

Figure 5 is a top plan view thereof, and Figure 6 is a central vertical section taken therethrough.

Referring now to Figures 1, 2 and 3 wherein I have, for the purposes of illustration, shown my invention in connection with the tappet 10 of an enclosed type valve 11, it is known that with respect to the lower end of the stem 12 of such valves the upper end of the corresponding tappet is usually slightly spaced to provide clearance, allowing for the expansion of the metal. In this construction the upper portion of the tappet 10 is usually provided with a threaded bore 13 for the reception of an adjusting screw whose upper head forms the valve stem engaging surface of the tappet and whose adjustment thus controls the clearance between the tappet and the valve stem. This adjusting screw is usually locked by a nut threaded thereon to bear against the upper end of the tappet.

My invention proposes a silencer which as applied to valves of the above type includes a cylindrical shell 13, externally threaded to screw into the bore 10^a of the tappet 10, having a reduced portion at one end and having at its opposite end an enlarged polygonal head 14 to facilitate adjustment thereof in the tappet bore, a lock nut 15 being employed thereon to lock the shell in adjusted position within the tappet bore. This shell 13 has an axial bore 16 and is provided at its reduced end with a small opening 17 forming a vent and oil port and at its headed end with a counterbore 18, its main bore 16 receiving in slidable relation a stem 19 provided with a head 20 beyond and normally spaced from the head 14 of the shell.

Around the stem 19 adjacent to the head 20, a bushing 21 is disposed, this bushing being movable in the counterbore 18 of the shell and being utilized with or without a fiber or other washer 22 around the inner surface of the head 20. The shell bore 16 also receives a spring 23 which is compressed between the inner end of the shell and the inner end of the stem 19 so that the latter is thus tensioned and maintained in its outer position except when the tappet is moved upwardly to unseat the valve.

The permissible movement between the head 20 of the stem 19 and the head 14 of the shell 13 provides for the adjustment of the parts so that the head 20 is in contact with the lower end of the valve stem 12 at all times, relative movement between the head 20 of the stem and the head 14 of the shell compensating for expansion of the parts in use. I have shown the shell 13 as provided with a pin 24 fitting transversely through its head 14 and through slotted openings 25 of the stem 19 and bushing 21 which thus holds the stem against rotation, supports the parts in the assembled position, and prevents the spring 23 from forcing the stem entirely out of the shell before it is inserted in the effective position illustrated in Figure 1. I have also shown the shell 13 as provided with inclined oil openings 26 whose inner ends communicate with the bore 16 intermediate the ends of the shell and whose outer ends open into oil grooves 27 in the outer face of the head 14.

My invention as applied to the rocker arm 28 of an overhead valve arrangement con-

templates an externally threaded cylindrical shell 13^a illustrated in Figures 4, 5 and 6 which is adapted to be screwed through one end of the rocker arm and locked in connection therewith by a lock nut 15^a, this shell having a cylindrical bore 16^a through which a stem 19^a is extended. The stem in this instance has bearing by virtue of a bushing 21^a in one end of the bore, adjacent to the engaging head 20^a of the stem which is spaced from the adjacent end of the shell with or without an interposed fiber or other washer 22^a. At its other end the stem has bearing through a reduced opening 17^a of the shell, the end of the shell adjacent to opening 17^a being transversely slotted as at 29 so as to form a guide for the reception of a pin 24^a which extends through the stem 19^a and thus movably holds the stem in connection with the shell 13^a and also provides for the reception of a screw driver or like implement for adjusting the shell 13^a in the rocker arm 28 after the lock nut 15^a has been loosened. The result of this construction is obviously the same, however, as that described with respect to Figures 1, 2 and 3, and it is equally obvious that my invention according to both constructions may be applied with ease and facility in actual operative connection with those parts of valve actuating connections where clearance

must ordinarily be left in view of the expansion of the parts when heated. This form of the invention has oil openings 26^a inclined therein and communicating with the bore 16^a.

It is also obvious my invention provides a simple inexpensive device of this nature which will eliminate the usual noises, known as valve taps and that it will obviate necessity for the fine careful adjustments ordinarily required.

I claim:

A valve silencer including an externally threaded shell adapted for adjustable positioning within a tappet, rocker arm and the like, said shell having a bore for the major portion of its length and a reduced opening through one end, a stem having a movable bearing within the bore and having a head at its outer end beyond one end of the shell, a spring within the bore of the shell for moving the stem in an outward direction, and a pin through a portion of the stem and through an adjacent portion of the shell to limit spring actuated movement of the stem said shell having inclined oil feed openings extending therein from a point adjacent to its upper end and opening at their lower ends into the said bore intermediate the ends of the latter.

ALFRED F. BORSCHEL.
